[57] CLAIM

The ornamental design for a seat, as shown and described.

DESCRIPTION

FIG. 1 is a front elevational view of a seat showing my design in the form of a chair;

FIG. 2 is a front elevational view of a seat showing my design in the form of a settee;

FIG. 3 is a front elevational view of a seat showing my design in the form of a couch;

FIG. 4 is a side view of the seat of FIG. 1 shown in its upright position; and

FIG. 5 is a side elevational view thereof in its inclined position;

FIG. 6 is a front elevational view of a modified form of the seat shown in FIG. 1; and

FIG. 7 is a rear perspective view thereof.

The sides of the seat forms not shown are mirror images of the side shown in FIG. 4.
